[57] CLAIM

The ornamental design for a combined chopping board and funnel, as shown and described.

DESCRIPTION

FIG. 1 is a top perspective view of a combined chopping board and funnel showing my new design;
FIG. 2 is a top plan view thereof;
FIG. 3 is a front elevational view thereof which is a mirror image of the rear elevational view;
FIG. 4 is a bottom plan view thereof;
FIG. 5 is a left side elevational view; and
FIG. 6 is a right side elevational view.

*Fig. 1**Fig. 5**Fig. 2**Fig. 6**Fig. 3**Fig. 4*
